H. TUECKMANTEL.
ANGLE IRON OR BRACKET FOR ENGLISH OR SEWED-IN BAGS.
APPLICATION FILED MAR. 20, 1914.

1,127,830.

Patented Feb. 9, 1915.

UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

ANGLE-IRON OR BRACKET FOR ENGLISH OR SEWED-IN BAGS.

1,127,830.

Specification of Letters Patent. Patented Feb. 9, 1915.

Application filed March 20, 1914. Serial No. 825,982.

To all whom it may concern:

Be it known that I, HUGO TUECKMANTEL, a citizen of the United States, residing at Irvington, in the county of Essex and State of New Jersey, have invented certain new and useful Improvements in Angle-Irons or Brackets for English or Sewed-In Bags; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in frames for traveling bags, satchels, and other bags; and, the invention has reference, more particularly, to a bag-frame and novel angle-irons or brackets therefor to be used in the construction of that class of traveling bags known as "English" or "sewed-in" bags.

In the usual forms of "sewed-in" bags, as at present manufactured, the stitching or sewing must be done by hand, because with the use of the ordinary construction of the "English" or "sewed-in" bag-frame it is impossible by means of a sewing-machine to stitch through the interstices of the bag-frames; while in other forms of "English" or "sewed-in" bag-frames it is possible to sew by machine except at the several points where the frames are provided with the usual angle-irons or brackets, at which points the operation of the sewing-machine must be stopped, the leather-portions of the bag-body being blind-stitched by hand above the metal surfaces of the angle irons or brackets at such points.

Aside from the time consumed and the additional cost of manufacture in thus blind-stitching the leather-portions of the bag-body located directly over the angle-irons or brackets, there is also great danger of striking the angle-irons or brackets by the needles used in the sewing-machine, thus very often breaking off the needles, and also damaging the leather as well as rendering the sewing machine inoperative.

My present invention, therefore, has for its principal object to provide an "English"

or "sewed-in" bag-frame which to all appearances is the same as an ordinary "English" or "sewed-in" bag-frame, but is provided with angle-irons or brackets of such novel and simple construction, that a strong bag-frame is produced, and that the machine-stitching or sewing of the leather bag to the frame is not interfered with; in other words, that the leather body-portions of the traveling-bag, satchel, or other bag, are readily sewed thereto by means of machine-stitching or sewing in one continuous operation from one end of the frame to the other end of the same, and that the usual hand-sewing or the blind-stitching over the angle-irons or brackets is avoided.

The invention has for its further object that, by the use of the bag-frame and angle-irons or brackets therefor, and embodying the principles of the present invention, "English" or "sewed-in" bags may be manufactured at a greatly reduced cost and a saving in time and labor, and, furthermore, "English" or "sewed-in" bags of improved appearance will be the result by reason of the evenness and continuity of the machine-stitching.

With the various objects of the present invention in view, the invention consists, primarily, in the novel bag-frame herein-after set forth; and the invention consists, furthermore, in the novel arrangements and combinations of the construction of the said parts, all of which will be more fully described in the following specification, and then finally embodied in the clauses of the claim which are appended to and which form an essential part of the said specification.

The invention is clearly illustrated in the accompanying drawings, in which:—

Figure 1 is a front elevation of an "English" or "sewed-in" bag-frame and the novel angle-irons or brackets therefor; Fig. 2 is a detail transverse section of the same taken on line 2—2 in said Fig. 1, this view being drawn on an enlarged scale; and Fig. 3 is a detail vertical cross section of the same, taken on line 3—3 in said Fig. 2. Fig. 4 is a detail transverse section of one of the sections of an "English" or "sewed-in" bag-frame illustrating a modified form

of the novel angle-irons or brackets therefor; Fig. 5 is a vertical cross section taken on line 5—5 in said Fig. 4; and Fig. 6 is a longitudinal section through the novel angle-iron or bracket, taken on line 6—6 looking in the direction of the arrow *x*. Fig. 7 is a detail transverse section of one of the sections of an "English" or "sewed-in" bag-frame illustrating a still further modified form of the novel angle-irons or brackets therefor; Fig. 8 is a vertical cross section taken on line 8—8 in said Fig. 7; and Fig. 9 is a horizontal section through the novel angle-iron or bracket, taken on line 9—9 looking in the direction of the arrow *y*. Fig. 10 is a detail transverse section of one of the sections of an "English" or "sewed-in" bag-frame illustrating a still further modified form of the novel angle-irons or brackets therefor; Fig. 11 is a vertical cross section taken on line 11—11 in said Fig. 10; and Fig. 12 is a horizontal section through the novel angle-iron or bracket, taken on line 12—12 looking in the direction of the arrow *z*.

Similar characters of reference are employed in the above described views, to indicate corresponding parts.

Referring now to the said drawings the reference character 1 indicates a complete "English" or "sewed-in" bag-frame, consisting of an upper frame or body-section 2 and a lower frame or body-section 3. To the said frame-section 2 is secured, by means 30 of the angle-irons or brackets, to be presently more fully described, the side frame-section or plate 4, and secured to the said frame-section 3, by means of the angle-irons or brackets to be presently more fully 35 described, is the side frame-section or plate 5, said side frame-sections or plates 4 and 5 being pivotally connected or hinged, as at 6, and as shown in Fig. 1 of the drawings.

As shown in the accompanying drawings, 45 the angle-irons or brackets to be presently described, interconnect the respective frame or body-sections 2 and 3 with their respective side frame-sections or plates 4 and 5 so as to provide intervening sewing-spaces 7 through which the stitches joining together 50 the leather covering of the bag-frame and the body-portions of the bag itself are passed by the action of the needle of the sewing-machine.

Referring now, more especially, to Figs. 1, 2 and 3 of the drawings, I have illustrated 55 therein one form of the novel angle-iron or bracket above referred to, the same comprising a horizontally extending ear or fastening member 8 at its upper end, a vertically extending ear or fastening member 9 at its lower end, and an interconnecting and integrally formed spacing member or strut 10. The horizontally extending ears or fas-

tening members 8 of said novel angle-irons 65 or brackets are adapted to be secured, by any suitable fastening means or process, such as rivets or by welding, to the under surfaces of the respective frame or body-sections 2 and 3 of the bag-frame, and in 70 like manner, the vertically extending ears or fastening members 9 are adapted to be secured to the inner surfaces of the respective side frame-sections or plates 4 and 5. When said angle-irons or brackets are thus 75 secured in connection with the respective members of the bag-frame said spacing members or struts 10 extending between the fastening members or ears 8 and 9 hold said side frame-sections or plates 4 and 5 respectively and properly spaced away from their 80 respective frame or body-sections 2 and 3 so as to provide said intervening sewing-spaces 7. Said spacing members or struts 10 are twisted at or adjacent to their junction 85 with the respective ears or fastening members 8 and 9, as shown at 11 and 12, so that the main body of said spacing members or struts 10 are presented at right angles to the plane of said sewing-spaces 7, 90 and are therefore presented edgewise in the sewing-spaces, and since the material of which the angle-irons or brackets are made is comparatively thin stock, the said struts 10, as thus arranged, offer no obstruction to 95 the reciprocation of the sewing-machine needle through the sewing-spaces 7. And even though the needle should strike the edge of said struts 10, the same would be readily deflected; that is, it would glance off 100 of the same and easily pass the strut without danger of bending or breaking the said needle.

Referring now to Figs. 7, 8 and 9 of the drawings I have illustrated therein a modified construction of the novel angle-iron or bracket, the same comprising the upper horizontal ear or fastening member 13 and the lower vertical ear or fastening member 14, the same being secured to the bag-frame 110 members by rivets 15, or otherwise as desired. The intervening spacing member or strut 16 in this construction is formed by folding the body of the angle-iron or bracket together so that the side vertical edges 17 115 are registered together, and in this manner providing a very stiff strut presented at right angles or edgewise to the plane of the sewing-openings 7. This construction provides a rounded edge 18 at the front or face 120 of the sewing-spaces 7, which will readily deflect the sewing-machine needle if the latter should happen to contact therewith.

Referring now to Figs. 7, 8 and 9 of the drawings, I have illustrated therein another 125 modified form of my novel angle-iron or bracket, the same comprising the upper horizontal ear or fastening member 19 and the

lower vertical ear or fastening member 20, the same being secured in the bag-frame members by welding, or in any other suitable manner. The intervening spacing-
5 members or struts 21 in this construction are formed by dividing the body of the angle-iron or bracket vertically, and then twisting each portion at or adjacent to their junctures with the respective ears or fastening-
10 members 19 and 20, as shown at 22 and 23, so that a pair of spacing-members or struts are presented at right angles or edgewise to the plane of the sewing-spaces 7, thus providing a very strong construction,
15 having all the advantages of the constructions already above described.

Referring now to Figs. 10, 11 and 12 of the accompanying drawings, I have illustrated therein still another modified construction of the novel angle-iron or bracket embodying the principles of the present invention, the same comprising the upper horizontal fastening-member or ear 24, and the lower vertical fastening-member or ear 25, the same being secured to the bag-frame members by welding, or in any other suitable manner. The intervening spacing-member or strut 26 is formed by doubling the body of the angle-iron or bracket upon itself adjacent to the respective ears or fastening members, as at 27, and in such a manner as to present the strut or spacing member 26 at right angles or edgewise to the sewing-spaces 7, whereby the advantages 35 above mentioned are secured.

I am aware that some changes may be made in the general arrangements and combinations of the various parts comprising the frame for use with "English" or "sewed-in" bags, and the novel angle-irons or brackets therefor, without departing from the scope of the present invention as set forth in the foregoing specification and as defined in the claims appended thereto. 40 Hence, I do not limit my present invention to the exact arrangements and combinations of the various devices and parts as described in the said specification, nor do I confine myself to the exact details of 45 the construction of the said parts as illustrated in the accompanying drawings.

I claim:—

1. An angle-iron for securing together the members of an "English" or "sewed-in" bag-frame to provide continuous sewing spaces through said bag-frame comprising ears for securing said angle-iron to the members of the bag-frame, and an intervening strut so disposed between said ears as to be 55 presented edgewise to the sewing spaces of said bag-frame when said angle-iron is assembled with the members of said bag-frame.

2. An angle-iron for securing together the

members of an "English" or "sewed-in" bag-frame to provide continuous sewing-spaces through said bag-frame comprising a strut provided with fastening ears at each end for attachment to the members of said bag-frame, said strut being so disposed at 70 right angles to the planes of said ears as to be presented edgewise in the sewing-spaces of said bag-frame when said angle-irons are secured with the respective members of said bag-frame.

75

3. An "English" or "sewed-in" bag-frame comprising upper and lower frame-sections and side-plates, angle-irons or brackets connected with the respective upper and lower frame-sections and the side-plates, so as to provide sewing-spaces between the upper and lower frame-sections and their respective side-plates, said angle-irons or brackets being formed with struts arranged to extend edgewise through said sewing-spaces and at right angles to the plane of the latter.

80

4. An "English" or "sewed-in" bag-frame comprising upper and lower frame-sections and side-plates, angle-irons or brackets connected with the respective upper and lower frame-sections and the side-plates, so as to provide sewing-spaces between the upper and lower frame-sections and their respective side-plates, said angle-irons or brackets being formed with struts arranged to extend edgewise through said sewing-spaces and at right angles to the plane of the latter, and fastening-ears at each end of said struts for attachment respectively to said frame-sections and their respective side-plates.

95

5. An "English" or "sewed-in" bag-frame comprising upper and lower frame-sections and side-plates, angle-irons or brackets connected with the respective upper and lower frame-sections and the side-plates, so as to provide sewing-spaces between the upper and lower frame-sections and their respective side-plates, said angle-irons or brackets being formed with struts arranged to extend edgewise through said sewing-spaces and at right angles to the plane of the latter, horizontally extending fastening ears at the upper ends of said struts for attachment to said frame-sections, and vertically extending fastening-ears at the lower ends of said struts for attachment to the respective side-plates of said frame-sections.

110

6. An angle-iron or bracket for connecting the members of "English" or "sewed-in" bag-frames comprising a pair of ears for attachment with the respective members of each frame section of the bag-frame, and an integrally formed intervening strut-portion extending between said ears, said strut-portion being provided with twisted-

115

120

125

125

125

portions at each end adjacent to the junction of said strut-portion with said ears, and whereby the main body of said strut-portion is presented at right angles or edge-wise to the planes of said ears.

5 In testimony, that I claim the invention

set forth above I have hereunto set my hand this 18th day of March, 1914.

HUGO TUECKMANTEL.
